(Cl. D61—1)

FIG. 1

FIG. 2

FIG. 3

FIG. 4

FIG. 5

FIG. 6

FIG. 1 is a top front perspective view of a foldable rear projection viewer or similar article showing my new design;

FIG. 2 is an enlarged side elevational view thereof, the opposite side being substantially a mirror image;

FIG. 3 is a front elevational view to the same scale;

FIG. 4 is a top plan view to the same scale;

FIG. 5 is a rear elevational view to the same scale; and FIG. 6 is a bottom plan view thereof.

Portions of the figures are diagonally lined to show a translucent screen in the upper portion of the viewer and a mirror in the lower portion.

I claim:

The ornamental design for a foldable rear projection viewer or similar article, substantially as shown and described.
